UNITED STATES PATENT OFFICE.

WILLIAM M. HOWE, OF AUSTIN, MINNESOTA.

CUFF-HOLDER.

SPECIFICATION forming part of Letters Patent No. 527,062, dated October 9, 1894.

Application filed December 26, 1893. Serial No. 494,707. (No model.)

To all whom it may concern:

Be it known that I, WILLIAM M. HOWE, a citizen of the United States, residing at Austin, in the county of Mower and State of Minnesota, have invented certain new and useful Improvements in Cuff-Holders, of which the following is a specification, reference being had therein to the accompanying drawings.

My invention relates to cuff holders or devices for securing a cuff to the sleeve of the wearer, and has for its object to provide a holder which is simple in construction, efficient in operation, inexpensive to manufacture, and is so compact in form as to cause no discomfort or inconvenience to the wearer.

My improved holder permits of the ready removal or adjustment of the cuff and yet so effective is it in operation that all danger of accidental displacement of the cuff is avoided.

In the drawings, Figure 1 is a view of a cuff provided with my improved cuff holder and attached to a sleeve. Fig. 2 is a side view of the holder. Fig. 3 is a view looking toward the left in Fig. 2. Fig. 4 is a view looking toward the right, Fig. 2. Fig. 5 is a bottom view. Figs. 6 and 7 are detail views of parts of the holder.

The body or button portion of the holder consists of a circular head *a* and a shank *b* which latter is elliptical in cross section. A recess *c*, open on two sides, is formed in the bottom of said shank *b*, and at one end of the elliptical shank *b* is formed a lip *b'* which will be referred to hereinafter. A central hole *d* is made in said body portion through which body portion passes a rod or pin *e* of steel or other suitable metal, the lower end of said rod being bent at right angles to the body portion thereof and then curved to form what I term a circular needle. The upper end of the rod *e* is secured to a circular disk *h* which is preferably slightly larger in diameter than the circular head *a* of the body portion of the holder, and on which latter said disk turns freely, the outer edge *g* of said disk *h* being roughened or milled to give a better grasping surface. On the edge of the disk *h* is placed an arrow *g'* or other indicator which registers (see Fig. 3) with a corresponding mark on the circular head *a* to enable the wearer to determine when a complete revolution of said disk *h* has been made.

The parts when assembled are in the position shown in Fig. 2, with disk *h* seated on the circular head *a* and turning freely thereon. The rod *e*, to which said disk *h* is secured, turns within the body portion as the disk *h* is rotated, the circular needle *f* at the end of rod *e* being housed within the recess *c*. It will be observed that when the indicating arrow or mark on the disk *h* registers with that on the circular head *a* the point of the circular needle is in such position as to be guarded by the downwardly projecting portion *i* of the shank *b*.

The operation of the device is as follows: The shank *b* is forced through the holes of the cuff from the outside by inserting the lipped portion *b'* of the shank first, and the holes in the cuff are thus held open until the entire shank *b* has passed through. The lip *b'* will then engage the edges of the holes and prevent the holder from dropping out of the cuff, while the elliptically shaped shank *b* will hold the body portion in the position in which it is inserted and prevent it from turning in the holes of the cuff. Now the wearer, slipping the cuff on to the arm and adjusting it to the desired position, grasps the disk *h* between the thumb and finger and forces the inner end of the shank *b* against the sleeve, at the same time giving the disk one complete revolution; the distance the disk *h* must be revolved to accomplish this being indicated by the arrows referred to above, or by some other suitable index. It will be obvious that the pressure of the shank *b* against the sleeve will cause the fabric of the shirt to be forced into the open-sided recess *c* in the bottom of the shank so that it will be readily engaged by the circular needle *f* notwithstanding the fact that the latter is housed in the said recess. When it is desired to detach the cuff the disk *h* is revolved in the opposite direction and the needle will be withdrawn from the fabric, thus allowing the removal or adjustment of the cuff.

I preferably construct my improved cuff holder of metal, although it may be made of wood, celluloid, or any other suitable material.

Having thus described my invention, I claim and desire to secure by Letters Patent—

1. A cuff holder consisting of a body or but-

ton portion *a* provided with the shank *b* having the open-sided recess *c* at its end or bottom, of the rod or shank *e* fitted to turn in the said shank *b* and provided at one end 5 with the circular needle *f* housed in said recess and the disk *h* to which the other end of said rod or shank *e* is secured; so that by turning said disk *h* the said circular needle may be rotated in said recess *c* to cause it to 10 be engaged with or disengaged from the fabric of the shirt sleeve to which the cuff is to be secured.

2. A cuff holder comprising a body or button portion *a* provided with the elliptical shank *b* having the open sided recess *c* at its end or bottom and having also the projecting lip *b'*, of the rod or shank *e* fitted to turn in 15 the said shank *b* and provided at one end with the circular needle *f* housed in said recess and the disk *h* to which the other end of 20 said rod or shank *e* is secured.

3. In a cuff holder, the combination with

the body portion provided with an elliptical shank having a recess at its bottom or lower end and also a projecting lip, of a circular 25 needle within said recess, means for rotating the said needle, and an indicator or index for determining the position of said needle within the recess, substantially as described.

4. In a cuff holder, the combination with 30 the body portion consisting of the head *a* and the shank *b* provided with the open-sided recess *c* and the lip *b'*, of the disk or cap *h*, the rod *e* secured to said disk or cap and turning therewith, the circular needle *f* formed at the 35 end of said rod and turning within said recess *c*, and the indicator or index *g'*, substantially as described.

In testimony whereof I affix my signature in presence of two witnesses.

WILLIAM M. HOWE.
